Patented May 29, 1917.

UNITED STATES PATENT OFFICE.

FREDERICK C. GIESEKER, OF ELMWOOD, WISCONSIN.

COW-TAIL HOLDER.

1,227,606.

Specification of Letters Patent.

Patented May 29, 1917.

Application filed March 18, 1916. Serial No. 85,087.

To all whom it may concern:

Be it known that I, FREDERICK C. GIESEKER, a citizen of the United States of America, residing at Elmwood, in the 5 county of Pierce and State of Wisconsin, have invented certain new and useful Improvements in Cow-Tail Holders, of which the following is a specification, reference being had therein to the accompanying 10 drawing.

This invention relates to cow-tail holders and has for its principal object the production of a simple and efficient means for gripping the cow's tail, thereby preventing the 15 same from swinging when it is desired to prevent this action.

Another object of this invention is the production of a cow-tail holder which comprises a pair of gripping jaws formed from 20 a blank, which are so constructed as to efficiently grip the hind leg of a cow and at the same time engage the cow's tail so as to prevent the cow from swinging her tail.

Another object of this invention is the 25 production of a cow-tail holder wherein a resilient clamp is provided which is constructed so as to be swung to one side as the cow's tail is being passed in front of the same, at which time the clamp may be released so as to automatically grip the tail and prevent its accidental removal when the latter is engaging the cow's hind leg.

With these and other objects in view this 30 invention consists of certain novel combinations, constructions, and arrangements of parts as will be hereinafter fully described and claimed.

In the accompanying drawing:

Figure 1 is a side elevation of the cow- 40 tail holder illustrating the manner in which the same is used.

Fig. 2 is an enlarged detail inverted perspective view of the device.

Fig. 3 is a vertical sectional view through 45 the clamp and sleeve portion of the holder.

Fig. 4 is a detail perspective view of the clamp.

Referring to the accompanying drawing by numerals it will be seen that the enlarged 50 portion of the cow-tail holder is formed from a blank which is bent intermediate its ends to provide the sleeve 1 from which the jaws 2 extend. These jaws 2 are bowed throughout their entire length so as to conform somewhat in contour to the shape of a portion of a cow's hind leg. The sleeve 1

is provided adjacent its upper portion and along one side edge thereof with a plurality of inwardly bent teeth 3 for purposes to be hereinafter set forth.

The clamp comprises an elongated straight body 4 having an opening 5 formed in one side thereof. This clamp 4 is adapted to be positioned upon one side of the sleeve, as shown clearly in Figs. 1 and 3, so as to allow the headed rivet 6 to extend through the opening 5 and be carried by the sleeve 1 for fixedly retaining the clamp 4 in engagement with the side portion of the sleeve. This clamp is provided at its lower end with an inwardly bent lip 7 having teeth 8 formed upon its edge portion, so that when the clamp 4 is in its normal position the lip 7 will extend over the lower portions of the sleeve 1, thereby allowing the teeth 8 thereof to be carried adjacent the teeth 3. In order to spring this clamp 4 there is provided a button 9 having a rivet portion 10 formed thereon for fixedly retaining the same in engagement with the clamp 4.

When this cow-tail holder is in use the jaws may be sprung apart owing to the fact that the holder is formed preferably of resilient metal. When the jaws have been sprung apart wide enough to permit the same to pass partly around the hind leg of a cow it may be positioned upon the leg, as very clearly disclosed in Fig. 1. Prior to this action, however, the tail is positioned between the jaws so as to be passed back toward the sleeve 1. The button 9 may then be gripped and pulled away from the sleeve thereby causing the lip 7 to be moved so as to provide considerable space between the teeth 3 and 8. At this time the jaws may be passed partially around the cow's tail, as hereinbefore set forth, and may then be released. The resiliency of the jaws 2 will cause the same to spring to substantially their normal positions so as to bind upon a cow's leg and thus detachably or removably retain the holder upon the leg as shown. Of course, after the tail has been passed into the sleeve 1 it may be released by the gripping and releasing of the button 9. The resiliency of the clamp 4, owing to the fact that it is carried permanently by the headed rivet 6 will cause the clamp to spring toward its normal position, thereby causing the teeth of the lip 7 to bind upon the cow's tail upon one side while the teeth 3 formed upon the sleeve 1 will bind upon the cow's

tail at the opposite side, and in this manner the cow's tail will be efficiently and positively retained within the sleeve 1. In this manner it will be seen that the cow's tail will be securely held so as to prevent the cow from swinging her tail under any circumstances when the holder is secured to her leg.

From the foregoing description it will be seen that a very simple and efficient cow-tail holder has been provided which will positively hold a cow's tail by means of the teeth formed upon the sleeve and also upon the resilient spring clamp while the jaws formed upon the sleeve will positively bind upon the cow's leg, so as to prevent the accidental displacement of the holder when the same is in use.

What is claimed is:

10 A cow tail holder of the class described, comprising a sleeve having spaced side portions, gripping jaws extending from said

side portions, inwardly extending teeth formed upon a portion of said sleeve, a spring clamp carried by said sleeve said 25 spring clamp comprising a straight body portion, means passing through one end of said clamp for fixedly retaining the same in engagement with said sleeve, a lip extending at right angles to said clamp, said lip having teeth upon its forward edge, means carried by said clamp for facilitating the pulling or moving of one end of said clamp from said sleeve, whereby a cow's tail may be passed into said sleeve, at which time the 35 clamp may be released so as to spring to its normal position for allowing the teeth of said lip to engage the tail and hold the same in engagement with the teeth of said sleeve. 40

In testimony whereof I hereunto affix my signature.

FREDERICK C. GIESEKER.
